ISAAC SNOW, OF LAWRENCE, MASSACHUSETTS, ASSIGNOR TO U. S. BOBBIN & SHUTTLE COMPANY 1929, OF PROVIDENCE, RHODE ISLAND, A CORPORATION OF RHODE ISLAND

LATERAL TAKE UP DEVICE FOR SHUTTLES

Application filed February 5, 1931. Serial No. 513,636.

This invention relates to what is known in the trade as a take up device for shuttles.

In shuttles especially what are known as the automatic type where there is a threading chamber from which a diagonal slot runs to an eye in the side, in order to prevent the thread on the bobbin from being thrown off and also in order to keep out kinks and to keep the filling thread straight in the cloth, there is usually a tension device of some sort in the shuttle in front of the tip of the bobbin.

However, as the shuttle sometimes rounds and there are certain places when the thread between the tension device and the cloth becomes slack, some sort of device for taking up the slack is desirable.

I am aware that there are various more or less complicated devices intended for this purpose and I am aware that there are devices in which there is an arm pivoted on a lateral pivot to swing either to the right and left or up and down, such devices having usually a plurality of arms which co-operate with a plurality of fixed guides, the idea being to bend the thread into several bends thus taking up the slack.

An objection to a take up device or take up arm so pivoted near the bobbin tip and extending forward is the unequal pressure or force of the spring and of the thread on the back and front pins or fingers and the danger that the thread will become entangled in some of the many fingers and guides.

In place of such devices, I pivot a spring pressed single arm on the side opposite the shuttle eye, preferably in the shuttle block, in such position that it will normally extend almost horizontally across the threading chamber near the top but can be pulled down to near the bottom thereof when the thread is ordinarily running out. When the shuttle stops, however, the force of the spring arm is sufficient to take up the slack. Such an arm can swing laterally on a longitudinal pivot.

In the drawing, Fig. 1 is a plan view of a shuttle with the preferred type of take up in position.

Fig. 2 is a vertical section on line 2—2 of

Fig. 1 looking up in the direction of the arrow.

Fig. 3 is a vertical cross section taken on the line 3—3 of Fig. 1 looking toward the left in the direction of the arrow and somewhat enlarged.

Fig. 4 is a vertical section on the line 4—4 of Fig. 1 looking toward the right in the direction of the arrow.

Fig. 5 is a vertical section similar to Fig. 2 with some parts shown in full lines for clearness, of a modification of the construction shown in Fig. 1.

Fig. 6 is a vertical section of the wooden part of the shuttle viewed from the left on line 6—6 of Fig. 5, the metal parts being shown in full lines.

Fig. 7 is a front elevation of the metal block shown in Figs. 1 and 2 from the front as it appears removed from the shuttle.

Fig. 8 is an enlarged view looking up on Fig. 7.

Fig. 9 is a vertical sectional view substantially similar to Fig. 4 of a modification.

Fig. 10 is a vertical section on line 10—10 of Fig. 1 as viewed from the right in the direction of the arrow.

Fig. 11 is a plan view with parts broken away showing another type of shuttle.

In the drawing, S represents a shuttle having a bobbin chamber 10, threading chamber 11, an eye slot 12 and an eye 13 of any well known type, and a block recess 9 for a metal shuttle block B. This block B has a longitudinal thread passage 1 formed by a wall 2 on the side of the eye and on the opposite side by wall 8 of recess 9 and extending up and down in a recess 3 in the wood by a vertical projection 4. In projection 4 is a spring hole 5 threaded at 6 for an adjusting screw 7 for an adjusting spring 68.

Take up arm A is pivoted at 69 to the top of projection 4 by means of a suitable pivot pin 67 and extends at 60 in a substantially straight direction but is bent up at 61 at the free end or tip.

At 60 and also at 61 this arm should be very smooth and preferably of hard metal which will not be cut by the thread as it runs out.

G represents a guide plate which, as shown, is part of the block B, such plate extending from 20 at the top on the eye side over and down at 21 into the thread passage 1 and 5 extending forward at 22 as a nose from under which extends down and back a horn 23 of a well known type, but having near the bottom a lateral eye passage 24. I will call this lateral passage the lateral eye passage.

10 The front edge 25 of guide plate G forms the back side of the eye slot, the other side being indicated by 12.

26 represents a thread guide pin which, as shown is driven into the part of block B under plate G. This thread guide pin is substantially horizontal and is proximate the eye side of the threading chamber 11 and may extend diagonally across the eye passage 24, its position being such that thread

20 T from a bobbin such as H will run free except as herein described and bend at right angles around a vertical thread pin 27 of the usual type and thence under pin 26 and out the eye 13.

25 F represents a lateral guide fin which extends from under guide plate G at 50 in a slanting curve at 51 down to a hook 52 behind which is a fin passage 53 the top edge of which is substantially in line with the top 25 edge of the eye passage 24.

The parts are so arranged that if the thread F runs off from bobbin H on the first pick it will run over the part 60 of arm A and will then during subsequent picks be threaded

30 through the eye 13 and run around the pin 26 and through eye passage 24. The pull of the thread depresses the free end 61 of arm A and the thread slips down around hook 52 and guide pin 24 into passage 53.

40 When the shuttle is in motion, the thread runs nearly straight holding down the end 61 of arm A, but when there is slack and the force of the spring on the take up arm is sufficient, its curved end 61 is lifted and makes a

45 single bend in the yarn between the passage 24 and the passage 53 thus taking up the slack.

I prefer to use some type of friction device, such as C located behind block B.

50 The one shown includes a recess 80 from which downwardly extends a plate 84 carrying with it a piece of felt 82 in contact with another piece of felt 81 held in place by a metal support 85 the parts being in such position that if the thread T unwinds from the bobbin, it naturally slips into mouth 83 and is held with more or less force.

In Fig. 4, I show a modification of the guide fin which instead of extending out from 60 the side opposite the eye extends down as K from the eye side. It starts at 70 and slopes down at 71 in a direction which crosses the slope of the arm A when depressed, to a hook 72 having behind it fin passage 73 which corresponds with passage 53.

As shown in Fig. 9, in place of a take up arm with a separate spring, I can use as shown at L a combination arm and spring which fits into a spring hole 92 in the bottom of projection 90 and then extends up at 93 and is curved around at 94 under a head 91 thence out at 95 and bent up at 96 the whole being so made that, as shown by the dotted lines, when it is pulled down as by the thread T, it will slip under the hook 72 of a guide fin K.

I can use a guide fin extending from one side over and down towards the other starting at either side, as shown at F and K.

Where the fin starts from the side opposite the eye, such as F, the thread is more easily directed down as both the arm and the guide slope in the same direction and especially if the thread is unwinding in a direction which helps.

25 However, this very unwinding may have a slight tendency to cause the thread to slip out of the fin thread passage although this is unimportant because it will get back in again at the next pick.

The drag of the friction device such as C and the strength of the spring pressed laterally pivoted arm should be so adjusted that the drag of the friction and the pull of the thread through the shuttle eye will be sufficient to hold down the take up arm while the shuttle is moving, but when the shuttle has stopped and the drag from the friction C ceases, the strength of the spring of the lateral take up arm should be enough to pull back the slack through the shuttle eye.

While I have described my take up device or lateral take up member as particularly applicable to an automatic or self-threading shuttle, as shown in Fig. 1, it can equally well be applied to the old fashioned suction eye type shown in Fig. 11.

30 shows such a shuttle with a threading chamber 31 which is also part of the bobbin chamber in which there is a bobbin from which the thread such as 36 unwinds and an eye 32 which goes out the side of the shuttle from chamber 31.

Extending from the side opposite the eye over and down I show a thread guide fin 35 which is similar in all respects to F and pivoted at 34 to a metal insert 37, in a groove 38 in the wood, is a take up arm 33 similar in all respects to arm A.

The thread 36 after threading runs under fin 35 the lower edge of which is substantially level with the passage in eye 32 while the free end of the arm 33 is held down as the thread runs out ordinarily, but when the shuttle stops, arm 33 lifts and bends the thread between the fin passage in the fin 35 and eye passage in eye 32.

The hook such as 72 formed at the end of a fin thread passage such as 73 at the bottom of a guide fin such as K, or even the sloping

lower edge such as shown at the bottom of F, with the eye in the shuttle and the lower back part of the horn such as 23 either with or without the horizontal thread pins 26 and 27 will keep the thread down and in position over arm A and under the guide fin. The purpose, of course, is to cause the thread to hold down the take up arm or member such as A as the thread is running out while the shuttle is flying across and to continue to hold part of it down when this member A acts as a take up of the slack.

I claim:

1. The combination in a shuttle for automatic looms having a bobbin chamber from which a threading chamber extends forward and an eye slot which extends diagonally back from the threading chamber to an eye in the side of the shuttle; of a thread directing guide plate which extends from the top of the shuttle on the eye side over and down into the threading chamber and which terminates at the front in a nose from which a horn slopes down and back, said horn having behind its bottom end a lateral eye passage; a thread guide pin proximate said thread passage behind the horn on the side away from the shuttle eye; a lateral guide fin the top edge of which slopes from near the top of the shuttle down towards the eye side and has at the bottom a fin thread passage; and a take up member pivoted to the shuttle between the lateral eye passage and the fin thread passage on that side of the threading chamber which is opposite the eye, said take up member including an arm of such size and in such position that its free end which curves upward can swing down laterally of the shuttle proximate a line between the top of the lateral eye passage and the top of the fin thread passage; and spring means to keep said arm normally raised.

2. The combination in a shuttle for looms having a bobbin chamber from which a threading chamber extends forward and an eye slot which extends diagonally back from the threading chamber to an eye in the side of the shuttle; of a thread directing guide plate which extends from the top of the shuttle on the eye side over and down into the threading chamber and which terminates at the front in a nose from which a horn slopes down and back, said horn having behind its bottom end a lateral eye passage; a lateral guide fin the top edge of which slopes down from near the top of the shuttle and has at the bottom a fin thread passage; and a take up member pivoted to the shuttle between the lateral eye passage and the fin thread passage on that side of the threading chamber which is opposite the eye, said take up member including an arm of such size and in such position that its free end which curves upward can swing down laterally of the shuttle proximate a line between the top of the lateral

eye passage and the top of the fin passage; and spring means to keep said arm normally raised.

3. The combination in a shuttle for looms having a threading chamber, a lateral eye passage from the threading chamber to an eye in the side of the shuttle; of a lateral guide fin which slopes down from near the top of the shuttle and has at the bottom a fin thread passage; and a take up member pivoted to the shuttle between the lateral eye passage and the fin thread passage on that side of the threading chamber which is opposite the eye, said take up member including an arm of such size and in such position that its free end which curves upward can swing down laterally of the shuttle proximate a line between the top of the lateral eye passage and the top of the fin thread passage; and spring means to keep said arm normally raised.

4. The combination in a shuttle for looms having a threading chamber and an eye in the side of the shuttle; of a lateral guide fin which has at the bottom a thread fin passage; and a take up member pivoted to the shuttle between the eye and the fin thread passage on that side of the threading chamber which is opposite the eye, said take up member including an arm which can swing down laterally of the shuttle in a plane which rises substantially between the shuttle eye and the guide fin; and spring means to keep said arm normally raised.
